UNITED STATES PATENT OFFICE.

EDWARD O. BABCOCK, OF NIAGARA FALLS, NEW YORK.

CHANGEABLE EXHIBITOR.

1,115,884.

Specification of Letters Patent.

Patented Nov. 3, 1914.

Application filed August 20, 1913. Serial No. 785,689.

To all whom it may concern:

Be it known that I, EDWARD O. BABCOCK, a citizen of the United States, residing at Niagara Falls, in the county of Niagara and State of New York, have invented a new and useful Improvement in Changeable Exhibitors, of which the following is a specification.

This invention relates to changeable exhibitors of the type adapted to display a series of street or station designations successively, or to exhibit a series of advertisements or other announcements.

In accordance with the invention the street or station designations or advertisements are marked upon a flexible band which is moved intermittently to exhibit the successive names.

The present invention comprises improved mechanism for intermittently moving such a band and for reversing the direction of its travel so as to display the successive names in reverse order.

In the accompanying drawings: Figure 1 is a front sectional elevation of an apparatus embodying a preferred form of the invention, the front run of the name band and the guide rollers therefor being omitted in this figure for the sake of clearness. Fig. 2 is a front elevation of the apparatus on a small scale. Fig. 3 is a transverse vertical section on line III—III, Fig. 1. Fig. 4 is a similar section on line IV—IV of Fig. 1. Fig. 5 is a view similar to Fig. 3, parts being omitted and the cross head being moved to its extreme lower position. Fig. 6 is a view similar to Fig. 3, the guide bar being swung to the position which it occupies when the name band is being driven in the reverse direction. Fig. 7 is a longitudinal vertical section through the guide bar, cross head and supporting devices for the guide bar. Fig. 8 is an elevation of the lever for swinging the guide bar. Fig. 9 is a vertical longitudinal section through the clutches and a portion of the driving drum. Fig. 10 is a section through one of the clutches on line X—X of Fig. 9. Fig. 11 is a horizontal section on line XI—XI of Fig. 3, parts being omitted for the sake of clearness. Fig. 12 is a vertical section through the end of one of the clutch operating straps and the guide therefor, showing one of the cross head horns in engagement therewith. Fig. 13 is a view similar to Fig. 10, showing another position of the ratchet tooth.

Referring to the drawings in detail, 1 designates a suitable casing in the front of which is a window 2 through which the street names or advertisements are displayed. The names or advertisements are marked on a band 3 which passes behind this window. The band may be endless or not, as desired. As shown, the band is not endless but is wound at one end upon a spool 4 and at the other end upon a spool 5. The spools 4 and 5 have bearings at their ends journaled in the end walls of the casing or otherwise suitably supported. Also journaled in the end walls of the casing, or otherwise suitably supported, is a drive shaft 6 on which is mounted a drive drum 7. The band 3 passes from the spool 4 over a guide roller 8, down in front of the window 2, over a guide roller 9, then over the drive drum 7 and to the spool 5. The spools 4 and 5 act alternately as supply and take-up spools, the direction of movement of the band being controlled by the movement of the drum 7, which may be intermittently rotated in either direction.

The means for intermittently rotating the drum comprise a pair of clutches 10 and 11 mounted on the drive shaft 6. Each of these clutches comprises a member 12 fixed to the drive shaft in any suitable manner, as by means of a set screw 13, each of these members including a hub 14 having in it one or more notches 15. As shown, the hub is provided with two notches, the clutch being designed to rotate the drum through one-half a revolution each time it operates. The notches 15 have a substantially radial wall 16 and a wall 17 approximately at right angles thereto which may be designated, for convenience, the tangent wall. Each of the members 12 has a flange 18 thereon, an annular recess being formed between these flanges around the hub portions 14 of the members 12. In this annular recess are mounted a pair of movable clutch disks 19, one for each clutch. Slidably mounted in a recess in each of these clutch disks is a bolt 20 having a tooth 21 thereon adapted to engage in one of the notches 15. The vertical face of the tooth is adapted to engage the radial face 16 of the notch while the side of the bolt engages the tangent face 17 of the notch. A spring 22 attached to the disk engages a pin 23 in the projecting end of the bolt and tends at all times to lift this end of the bolt away from the clutch disk, that

is, the spring 22 tends to draw the vertical shoulder of the tooth 21 into engagement with the radial wall 16 of the notch 15. When the clutch disk is rotated in the direction of the arrow in Fig. 10, the side of the toothed bolt engages the tangent wall of the notch 15, causing the clutch disk to carry with it the hub member 14, the drive shaft, drive drum and name band. When 10 the clutch disk is rotated in the opposite direction, as indicated by the arrow in Fig. 13, the tooth 21 is lifted by its engagement with the radial wall 16 of the notch 15, sliding the bolt in its recess against the force of the 15 spring 22 and permitting the clutch disk to slide freely around the hub and drive shaft. Thus the oscillation or partial rotation in opposite directions of the clutch disk will drive the drive shaft intermittently in one 20 direction.

For producing oscillatory rotation of the clutch disks, each of the latter has fixed to it one end of one of a pair of flexible bands or straps 25, the other ends of which are 25 adapted to be connected with a reciprocating cross head 26. Only one of the clutches is used in driving the drive shaft and drum in one direction, the second clutch being provided for driving the drum in the reverse direction. Means are accordingly provided for connecting the cross head with only one of the straps at a time. For this purpose each of the straps has a lug 27 formed on its lower end, the end of the strap 30 and lug being perforated, as indicated at 28 (see Fig. 12). Guides 29 are provided for the straps, these guides having pockets 30 therein to receive the lugs 27, the walls of the pockets being notched as indicated at 40 31, to permit the horns of the cross head to enter and leave the pockets. The cross head 26 is provided on each side with a horn or hook 32 which is adapted to pass through the hole in the end of one of the straps and 45 thus connect the cross head to such strap. The cross head is slidably mounted upon a guide bar 35 which is movably supported in such manner that the cross head may be shifted between the strap guides in order to 50 connect it with either of the straps, as desired. When the cross head is disconnected from a strap, the end of such strap is drawn up snugly into the pocket 30, where it is held by the action of a spiral spring 36 55 mounted in recesses in the two clutch disks 19, the ends of the spring being connected to the two disks and tending to rotate them in such a way as to wind up the two straps 25. When the ends of the straps are held in 60 the pockets 30 it will be seen that one of the horns of the cross head may be engaged with the opening 28 in the end of either strap, by simply shifting the guide bar 35 and cross head from one side to the other. 65 Fig. 6 shows the cross head connected

to one of the straps, while Figs. 3 and 5 show it connected to the other strap, Fig. 5 showing the cross head and strap pulled down so as to rotate the clutch disk and turn the shaft and drum through a half revolution. In order to prevent one clutch from interfering with the rotation of the drive shaft by the other clutch, the guide bar 35 is provided with a pair of cams or wedges 40 on its upper end, 70 one of which is adapted to engage with the end of the toothed bolt 20 of the inoperative clutch for either position of the guide bar and push such toothed bolt into the clutch so as to hold the tooth 21 out of engagement 75 with the notches in the hub of the clutch. The position in which the toothed bolt is held by the cam 40 is approximately that shown in Fig. 13. The guide bar 35 may be supported in any suitable manner to permit of its being shifted so as to engage the cross head with one or the other of the clutch straps. As shown, the guide bar is mounted upon the end of a short shaft 41 journaled in a sleeve 42 attached to the end 80 wall of the casing. The end of the shaft 41 projects through the casing and has secured thereon a lever 43 by which the shaft may be turned and the guide bar 35 shifted from one position to the other. A suitable catch 85 may be provided to hold the guide bar in either of its positions, for example, the end of the lever 43 may carry a spring-pressed pin 44 adapted to engage with one of a pair of sockets 45 formed in a plate 46 attached to the casing. The pin is provided with a knob 47 by which it may be withdrawn to permit the lever to be shifted.

The operation of the device is accomplished by forcing the cross head 26 down from the position shown in Figs. 3 and 6 to the position shown in Fig. 5 and then permitting it to be drawn up to its initial position. Any suitable means may be utilized for this purpose. As shown, the cross head has attached to it one end of a chain 50 which passes over a guide roller 51, along the bottom of the casing and out through an opening in the end wall thereof. The cross head is drawn down by simply pulling this chain. When the chain is released the cross head will be returned to its initial position by the strap 25 to which it is connected, the strap being wound upon its clutch disk through the action of the spring 36. Each 110 time the chain is pulled the drive drum is rotated a half revolution and a new name or advertisement is displayed through the window 2. The chain may be pulled by hand or by a power device, as may be desired.

In order to prevent the drum 7 from traveling more than the desired distance when rotated by the mechanism described, a suitable stop mechanism is preferably pro- 130

vided. This may be of any desired construction, but, as shown, the drive shaft 6 has a disk 55 mounted thereon, this disk having one or more notches 56 formed in its periphery. As in the embodiment of the invention illustrated, the drum is intended to be rotated one-half a revolution each time the chain is pulled, the disk 55 is shown as provided with two diametrically opposite notches 56.

57 is a lever pivoted at 58 to the end wall of the casing or other suitable support, this lever having near its outer end a detent tooth 59 adapted to engage in one or the other of the notches 56. 60 is a second lever pivoted at 61 to the end wall of casing or other support and connected to the lever 57 by means of a connecting rod 62. The connecting rod 62 has stops 63 and 64 thereon between which is clamped the lever 57. The stop 64 is movable on the connecting rod and is forced against the lever 57 by a spring 65. The arm 66 of the lever 60 projects into the path of a lug 67 on the side 25 of the cross head 26, so that when the cross head is drawn down, the lug 67 engages the arm 66 of the lever 60, as shown in Fig. 5, and lifts the connecting rod 62. This causes the stop 64 to lift the lever 57 and force the detent tooth 59 into engagement with the periphery of the disk 55. As the movement of the connecting rod 62 is greater than the movement permitted the lever 57 before the tooth 59 strikes the periphery of 30 the disk, the rod will lift up through the hole in the lever and the stop 64 and thus compress the spring 65. The rotation of the disk 55, however, soon brings one of the notches 56 over the tooth 59 into which the tooth will at once be forced by the action of the spring 65. The rotation of the drum is thereupon arrested.

As the spools 4 and 5 act alternately as supply and take-up spools, it is desirable 45 to provide means for applying a brake to retard the revolution of the supply spool, so as to keep the band under proper tension, and also to provide means for rotating the take-up spool. In order to retard 50 the motion of the spool acting as a supply spool, a brake lever 70 is provided which is pivoted at 71 to the end of the casing or other suitable support and has pivoted to each end thereof a brake shoe 72. The lever 70 is connected by means of a connecting rod 73 to an arm 74 attached to the guide bar 35. Thus the shifting of the guide bar to engage the cross head with one or the other of the clutch straps also shifts 55 the brake lever 70 so as to apply one of the brake shoes 72 to the spool from which the name band is to be unwound. In order to rotate the spool which is to take up the name band, the spool is connected by suitable driving connections to the drive shaft 60 65

6. Such connections preferably comprise driving belts 80 passing over the ends of the spools and over pulleys 81 on the drive shaft. The belts 80 are normally so loose as to slip on the spools without rotating them, means being provided for tightening one or the other of the belts as it is desired to drive one or the other of the spools. The means shown for tightening each belt comprises a roller 82 mounted on the end of 70 an arm 83 pivoted to the end of the casing or other fixed support by a pivot 84. The rollers are adapted to be drawn into engagement with their belts by means of springs 85. Each of these springs is connected at one end to one of the arms 83 and at its other end, by means of a screw-threaded rod 86 or otherwise, to an abutment 87 on a movable plate 88. The tension of the springs 85 is so adjusted that when the plate 88 is shifted to one position, one of the springs 85 holds its arm 83 and roller 82 in contact with one of the belts 80, thus tightening that belt sufficiently to drive the corresponding spool while the other arm 83 and roller 90 95 82 are relieved from the tension of the other spring 85, so as to permit the second belt 80 to slide loosely upon its spool. Fig. 4 shows the plate 88 in full lines in position to tighten the belt for driving the spool 4, 95 while in dotted lines is indicated the position of the plate for tightening the driving belt for spool 5. For shifting the plate 88 any suitable means may be provided, these means preferably having an operative connection with the devices for shifting the guide bar 35. As shown, the plate is shifted by means of a lever 89 pivoted at 90 to a fixed support, the end of the lever opposite to that connected to the plate having a 100 pivotal connection with the arm 91 of the lever 74, which, as before stated, is connected to move with the guide bar.

The operation of the device is as follows: The band bearing the inscriptions which it 110 is desired to exhibit is wound on one of the spools and carried over the driving drum and guide rollers to the other spool. The lever 43 is then set in such position as to tension the belt on the take-up spool and apply the brake to the supply spool. The same movement of the lever 43 shifts the guide bar 35 into position to cause one of the cams on its end to hold the toothed bolt of one of the clutches on the driving shaft 115 in inoperative position and to cause one of the horns on the cross head 26 to pass through the hole in the end of the strap on the other clutch. The chain 50 is then pulled, drawing down the cross head and rotating the clutch, which in turn rotates the main shaft and the drive drum and advances the name band. When the cross head has nearly reached its lowest position the lug 67 on it strikes the lever 60 and lifts the de- 120 125 130

4. tent tooth into engagement with the detent disk 55. When the drive drum 7 has advanced the name band a proper distance, one of the notches 56 in the detent disk 5 comes opposite to the detent tooth and the latter snaps into the notch and stops the disk and drum. The chain 50 is then released, whereupon the cross head will be raised to its initial position by the pull exerted by the strap which is wound upon its clutch disk by the spring 36. The name band remains stationary until the chain 50 is again pulled, when it is advanced a predetermined distance to expose the next inscription thereon. Any number of inscriptions may be thus successively exhibited, depending only upon the length of the band. When it is desired to reverse the apparatus so as to expose the inscriptions in the reverse order, the lever 43 is shifted, thus disconnecting the cross head from the first clutch strap and connecting it with the other strap, and releasing the toothed bolt of the second clutch and moving the bolt of the 25 first clutch to inoperative position. At the same time the tension of the driving belts for the two spools is changed and the brake released from one spool and applied to the other. Pulling of the chain 50 will now cause the name band to advance intermittently in the opposite direction. Thus the throwing of the lever 43 makes all the changes necessary to cause the apparatus to work satisfactorily in either direction.

35. I claim as my invention:

1. In a changeable exhibitor, the combination of a name band, a driving drum therefor, means for rotating said drum including a reciprocatory member, a guide bar on 40 which said member is slidably mounted, said guide bar being adapted to occupy either of two positions to cause the reciprocatory member to turn said drum in one or the other direction, spools upon which said 45 name band is wound, means adapted to drive said spools from said drum, and means controlled by the position of said guide bar for causing the driving means to turn either one of said spools.

50. 2. In a changeable exhibitor, the combination of a name band, a driving drum therefor, means for rotating said drum including a reciprocatory member, a guide bar on which said member is slidably mounted, 55 said guide bar being adapted to occupy either of two positions to cause the reciprocatory member to turn said drum in one or the other direction, spools upon which said name band is wound, means adapted to 60 drive said spools from said drum, brakes for said spools, means controlled by the position of said guide bar for causing the driving means to turn either one of said spools, and means controlled by the position of the

guide bar to apply the brakes to the other 65 spool.

3. In a changeable exhibitor, the combination of a name band, a driving drum therefor, means for rotating said drum including a reciprocatory member, a guide 70 bar on which said member is slidably mounted, said guide bar being adapted to occupy either of two positions to cause the reciprocatory member to turn said drum in one or the other direction, spools upon 75 which said name band is wound, belts loosely connecting said spools and said drum, and means controlled by the position of said guide bar to tighten either of said belts for driving either one of the spools. 80

4. In a changeable exhibitor, the combination of a name band, a driving drum therefor, means for rotating said drum including a reciprocatory member, a guide bar on which said member is slidably mounted, said guide bar being adapted to occupy either of two positions to cause the reciprocatory member to turn said drum in one or the other direction, spools upon which said name band is wound, belts loosely connecting said spools and said drum, brakes for 90 said spools, means controlled by the position of said guide bar to tighten either of said belts for driving either one of said spools, and means controlled by the position 95 of said guide bar to apply the brakes to the other spool.

5. In a changeable exhibitor, the combination of a name band, a driving drum therefor, means for rotating said drum including a reciprocatory member, a guide bar on which said member is slidably mounted, said guide bar being adapted to occupy either of two positions to cause the reciprocatory member to turn said drum in one or the other direction, spools upon 100 which said name band is wound, brakes for said spools, and means controlled by said guide bar to apply the brakes to one of said spools when the guide bar is in one position 110 and to apply the brakes to the other spool when the guide bar is in the other position.

6. In a changeable exhibitor, the combination of a name band, a driving drum over which said band passes, means for rotating 115 said drum in either direction, spools upon which said band is wound, belts which impart rotary motion from said drum to said spools, one of said belts passing around each of said spools, and means for tensioning the belt passing around the spool acting as a take-up spool, and releasing the tension from the belt passing around the other spool, for either direction of movement of the driving drum. 120

7. In a changeable exhibitor, the combination of a name band, a driving drum, means for rotating said drum in either di- 125

rection, spools upon which said name band is wound, belts for imparting rotary motion from said driving drum to said spools, said belts being normally loose enough to 5 slip without driving said spools, movable tensioning devices adapted to tension said belts to cause the same to drive said spools, springs connected to said tensioning devices, and a movable member to which 10 said springs are connected, said member when moved in one direction tensioning one of said springs and releasing the tension on the other spring, and vice versa.

8. In a changeable exhibitor, the combination of a name band, reversible driving means therefor including straps and a device adapted to engage either of said straps for actuating said driving means in different directions, spools upon which said 20 band is wound, a brake lever having a brake at each end, one of said brakes being adapted to contact with one of said spools when the other brake is out of contact with the other spool, and vice versa, and means 25 for throwing said lever to release the brake from one spool and apply the brake to the other spool when the strap engaging device is moved from a position to engage one of the straps to a position to engage the other 30 strap.

9. In a changeable exhibitor, the combination of a name band, a driving drum therefor, and means for rotating said drum intermittently comprising a clutch, a strap 35 winding on said clutch, a guide bar, a cross head sliding on said guide bar and engaging said strap, a flexible connector attached to said cross head for drawing the same away from said clutch and unwinding said 40 strap therefrom, and means for returning said cross head to its initial position.

10. In a changeable exhibitor, the combination of a name band, a driving drum therefor, and means for rotating said drum intermittently comprising a clutch, a strap 45 winding on said clutch, a guide bar, a cross head sliding on said guide bar, means for drawing said cross head away from said clutch to unwind the strap therefrom, and 50 a spring for rotating said clutch to rewind the strap and draw said cross head to its initial position.

11. In a changeable exhibitor, the combination of a name band, a driving drum therefor, and means for rotating said drum intermittently in either direction comprising 55 a pair of clutches mounted on the drum shaft, straps wound on said clutches in opposite directions, a cross head adapted to be engaged with one or the other of said straps, and means for reciprocating said cross head.

12. In a changeable exhibitor, the combination of a name band, a driving drum

therefor, means for rotating said drum intermittently in either direction comprising 65 a pair of clutches mounted on the drum shaft, straps wound on said clutches in opposite directions, a movable guide bar, a cross head on said guide bar, means for shifting said guide bar to engage said cross head with one or the other of said straps, and means for reciprocating said cross head.

13. In a changeable exhibitor, the combination of a name band, a driving drum 75 therefor, means for rotating said drum intermittently in either direction comprising a pair of clutches mounted on the drum shaft, straps wound on said clutches in opposite directions, a movable guide bar, a 80 cross head on said guide bar, means for shifting said guide bar to engage said cross head with one or the other of said straps, means for reciprocating said cross head, and means on the guide bar for disconnecting one 85 or the other of said clutches from driving engagement with the shaft of said driving drum.

14. In a changeable exhibitor, the combination of a name band, a driving drum therefor, means for rotating said drum intermittently in either direction, said means including a pair of clutches mounted on the shaft of said driving drum, each of said clutches having a bolt adapted to engage a member 95 fixed to said shaft, one of said clutches acting to drive the shaft in one direction and one in the other direction, straps wound on said clutches in opposite directions, a movable guide bar having its end shaped to 100 move the bolt of one of said clutches to inoperative position when it is in one position and to release said bolt and move the bolt of the other clutch into inoperative position when it is in its other position, a cross head 105 mounted upon said guide bar and adapted to be engaged with one or the other of said clutch straps depending upon the position of said guide bar, and means for reciprocating said cross head.

15. In a changeable exhibitor, the combination of a name band, a driving drum therefor, and means for rotating said driving drum intermittently including a clutch, a strap wound thereon, a guide for the end 115 of said strap, a cross head having means thereon adapted to engage the end of said strap, said means being adapted to engage the end of said strap when the latter is in said guide, and means for reciprocating said 120 cross head.

16. In a changeable exhibitor, the combination of a name band, a driving drum therefor, and means for rotating said drum intermittently in either direction, including 125 a pair of clutches, straps wound thereon in opposite directions and having holes in their ends, guides for the ends of said straps,

a cross head movable between said guides, said cross head having horns projecting from opposite sides thereof, means for shifting said cross head to cause one of its horns to enter the hole in the end of one of said straps, and means for reciprocating said cross head.

17. In a changeable exhibitor, the combination of a name band, a driving drum therefor, spools upon which said band is wound, means for rotating said driving drum intermittently in either direction, said means including clutches, straps wound thereon in opposite directions, a movable 10 guide bar, a cross head mounted thereon adapted to be engaged with either of said straps, and means for reciprocating said cross head, driving devices for each of said spools, and combined means for shifting 15 said guide bar to disengage said cross head from one of said straps and engage it with the other strap and for disconnecting the driving means for one of said spools and throwing into operation the driving means 20 for the other spool.

18. In a changeable exhibitor, the combination of a name band, a driving drum therefor, spools upon which said band is wound, means for rotating said driving 30 drum intermittently in either direction, said means including clutches, straps wound thereon in opposite directions, a movable guide bar, a cross head mounted thereon adapted to be engaged with either of said 35 straps, and means for reciprocating said cross head, brakes for said spools, and combined means for shifting said guide bar to disconnect said cross head from one of said straps and connect it with the other strap 40 and for applying the brake to one of said spools and removing the brake from the other spool.

19. In a changeable exhibitor, the combination of a name band, a driving drum 45 therefor, spools upon which said band is wound, means for rotating said driving drum intermittently in either direction, said means including clutches, straps wound

thereon in opposite directions, a movable guide bar, a cross head mounted thereon adapted to be engaged with either of said straps, and means for reciprocating said cross head, driving means and brakes for said spools, and combined means for shifting said guide bar to disengage said cross 55 head from one of said straps and engage it with the other of said straps, for disconnecting the driving means for one of said spools and for applying the brake to said spool and for throwing into operation the driving 60 means for the other spool and removing the brake from said spool.

20. In a changeable exhibitor, the combination of a name band, a driving drum therefor, means for intermittently rotating 65 said drum including a clutch, a strap wound thereon, a cross head connected to said strap, means for reciprocating said cross head, a notched disk connected with said drum, a detent tooth adapted to engage with a notch in said disk, and means for throwing said detent tooth into engagement with said disk including a member tripped by said cross head when the latter is moved away from said clutch.

21. In a changeable exhibitor, the combination of a name band, a driving drum therefor, means for intermittently rotating said drum including a clutch, a strap wound thereon, a cross head engaging said strap, 80 means for reciprocating said cross head, a notched disk connected to said drum, a detent tooth adapted to enter a notch in said disk, a lever on which said tooth is mounted, a second lever having an arm adapted to be 85 engaged by a part of said cross head when the latter is moved away from said clutch, a connecting rod between said levers, and a yieldable connection between said rod and one of said levers.

Witness my hand, this 18 day of August, 1918.

EDWARD O. BABCOCK.
